DESIGN FOR A TELEPHOTO RECORDER

Austin G. Cooley, Rutherford, N. J.

Application June 10, 1937, Serial No. 69,780

Term of patent 14 years

To all whom it may concern:

Be it known that I, Austin G. Cooley, a citizen of the United States of America and residing at Rutherford, in the county of Bergen and State of New Jersey, have invented a new, original, and ornamental Design for a Telephoto Recorder, of which the following is a specification, reference being had to the accompanying drawing, forming a part thereof in which:

Fig. 1 is a front view of a telephoto recorder showing my new design.

Fig. 2 is a side view of the recorder of Fig. 1 with certain of the parts shown in dotted outline.

What I claim is:

The ornamental design for a telephoto recorder substantially as shown.

AUSTIN G. COOLEY.
